PREFABRICATED BATH FACILITY

Hendrik de Kanter, 4620 Alla Road,
Culver City, Calif.

Filed Aug. 28, 1964, Ser. No. 81,501

Term of patent 14 years

(Cl. D4—4)

The dominant features of the design reside in the portions shown in solid line.

I claim:

The ornamental design for a prefabricated bath facility, substantially as shown and described.
